H. W. BOLENS.
VALVE GEARING FOR INTERNAL COMBUSTION ENGINES.
APPLICATION FILED JUNE 28, 1912.

Patented Mar. 10, 1914.

UNITED STATES PATENT OFFICE.

HARRY W. BOLENS, OF PORT WASHINGTON, WISCONSIN.

VALVE-GEARING FOR INTERNAL-COMBUSTION ENGINES.

1,089,526.

Specification of Letters Patent. Patented Mar. 10, 1914.

Application filed June 28, 1912. Serial No. 706,450.

To all whom it may concern:

Be it known that I, HARRY W. BOLENS, a citizen of the United States, and resident of Port Washington, in the county of Ozaukee and State of Wisconsin, have invented certain new and useful Improvements in Valve-Gearing for Internal-Combustion Engines; and I do hereby declare that the following is a full, clear, and exact description thereof.

My invention refers to internal combustion engines of the hit and miss type, its object being to provide simple, positive and effective governor-controlled valve-gear therefor.

In engines of the above mentioned type it is usual to employ a governor-controlled sleeve that is mounted upon the engine crank-shaft and is moved longitudinally thereupon by its governor connection. A hit or miss engagement between a valve-rod and an interposed member is dependent upon the position of the sleeve and the exhaust valve may be held open to thus break the vacuum upon the suction stroke of the piston, whereby a gas charge is skipped, this operation being governed by the speed and load conditions to which the engine is subjected.

The specific object of my invention is to provide an oscillatory arm having a tappet at its free end, which tappet is adapted to limit reciprocative motion of the valve-rod in one direction, said arm being oscillated through movement of the valve-sleeve whereby its tappet is caused to travel in or out of the lineal path of travel of the valve-rod.

With the above objects in view the invention consists in certain peculiarities of construction and combination of mechanical elements as hereinafter set forth with reference to the accompanying drawings and subsequently claimed.

In the drawings Figure 1 represents a plan view, partly in horizontal section, of a fragment of an internal combustion engine and valve-gearing therefor embodying the features of my invention; Fig. 2, an elevation of the same partly in section, the section being indicated by line 2-2 of Fig. 1, and Fig. 3, a detailed rear face view of the valve-rod head showing a tappet-plate in connection therewith and means for adjusting the same.

Referring by characters to the drawings,

1 represents a fragment of an engine bed provided with a journal-box 2 for the reception of an engine crank-shaft 3.

4 represents a fragment of the usual spring-controlled reciprocative valve-rod, the rear end of which is arranged to actuate the exhaust valve not shown. The forward end of the valve-rod terminates with a forked head 5, the tangs of which straddle the outer projecting end of an arbor 6. The arbor is journaled in the bearing 6' that forms part of the engine-bed, and serves as a support and guide for said valve-rod. The forked end of the valve-rod is held against lateral play upon the arbor end, between a valve-cam 7 and an ignition timing cam 7', both of which cams are secured to the arbor and arranged to abut the side faces of the valve-rod head. The arbor has also secured thereto the usual gear-wheel 8 that meshes with a pinion 9 carried by the engine crank-shaft 3, the said gearing constituting the usual drive mechanism for the spark timing cams. The valve-rod head 5 also carries an anti-friction roller 10 that is arranged to engage the valve-cam 7 whereby positive thrust of said valve-rod in opposition to a spring 4' is had, during each valve movement.

One of the valve-rod head tangs has an apertured ear 11 extending therefrom for the reception of a hardened metallic tappet-plate 12, the same being adjustably secured to said ear by a retaining bolt 13 that passes through the ear aperture, which aperture is elongated, and a corresponding circular aperture in the tappet-plate. The rear edge of the tappet-plate 12 is arranged to abut the end of an adjusting screw 14 which screw is in threaded union with a web extension of the ear 11. This screw permits adjustment in or out of the tappet-plate 12, the retaining bolt being thereafter confined by a suitable lock-nut.

The engine crank-shaft 3 carries the usual fly-wheel 15 provided with a centrifugal governor 16 in the form of a bell-crank. One arm 16' of the bell-crank is provided with a pin or stud that engages an annular groove 18 of a sleeve 19, the latter being loosely mounted upon said crank-shaft and is also provided with a second annular groove 18', which groove constitutes means for imparting oscillatory movement to a pivoted arm 20. The arm 20 extends over and beyond the crank-shaft and carries a roller stud 21 that engages the annular groove 18' of the

governor-controlled sleeve. The free end of the arm 20 is provided with a rectangular shouldered seat 22 for the reception of a tappet-plate 23, which tappet-plate is held to the arm-seat by a countersunk headed bolt 23', the bolt being retained by a suitable nut that engages the rear face of the arm and is in threaded union with said bolt. The arm tappet-plate and valve-rod tappet-plate are disposed upon the same horizontal plane whereby they abut each other as the arm tappet is moved into the path of travel of the rod in one direction, whereby travel of said rod is checked. Thus if the cam 7 has thrust the rod rearward to effect a valve opening movement and at this time, should the tappet of the oscillatory arm be brought into alinement with the valve-tappet, return movement of the valve-rod would be checked, whereby the valve is held open. Hence it is apparent that when the speed of the engine is accelerated to a predetermined degree that the arm tappet will be moved to a position whereby the exhaust valve is held open and during the succeeding cycle of the engine there will be no admission of a gas charge. The valve-rod 4 also carries an insulated spring terminal 7" which is adapted to engage the ignition cam 7' whereby the spark circuit is closed, this mechanism forming no part of my invention.

Attention is called to the fact that the head of the valve-rod being in the form of a fork, the assemblage of the device is facilitated and thus the valve-rod can readily be placed in position without the removal of parts or box attachments, which, under ordinary conditions are necessary in order to supply the proper guides for said rod.

I claim:

1. In an internal combustion engine having a bed, a shaft journaled therein, a valve-rod provided with a head in juxtaposition to the shaft, a governor-controlled grooved sleeve reciprocatively mounted upon the shaft, and a tappet-plate carried by the valve-rod head; the combination of a vertically disposed pin extending from the engine bed, an oscillatory arm mounted upon the pin, the arm being extended crosswise over the sleeve and having its free end disposed upon the opposite side of said sleeve from that of its fulcrum point, a stud extending from said arm intermediate of its length engageable with the sleeve groove, a tappet-plate secured to the free end of the aforesaid arm, the tappet-plate being arranged to oscillate across the line of travel of the valve head tappet, whereby the latter is engaged incidental to predetermined acceleration of the engine.

2. In an internal combustion engine having a bed, a shaft journaled therein, a valve-rod provided with a head in juxtaposition

to the shaft, a governor-controlled grooved sleeve reciprocatively mounted upon the shaft, and a tappet-plate carried by the valve-rod head; the combination of an oscillatory arm in pivotal union with the engine bed, the arm being extended crosswise of the sleeve and having its free end disposed upon the opposite side of said sleeve from that of its point of oscillation, a stud extending from the arm intermediate of its length engageable with the sleeve groove, a tappet-plate carried at the free end of said arm, the tappet-plate being in alinement with the valve-rod tappet-plate whereby movement of said valve-rod is checked in one direction. 80

3. In an internal combustion engine having a bed, a shaft journaled therein, a valve-rod provided with a head in juxtaposition to the shaft, a governor-controlled grooved sleeve reciprocatively mounted upon the shaft, and a tappet-plate carried by the valve-rod head; the combination of an oscillatory arm in pivotal union with the engine bed, the arm being extended crosswise of the sleeve and having its free end disposed upon the opposite side of said sleeve from that of its point of oscillation, a roller stud extending from the arm intermediate of its length engageable with the sleeve groove, a tappet-plate carried at the free end of said arm, the tappet-plate being in alinement with the valve-rod tappet-plate whereby movement of said valve-rod is checked in one direction. 95

4. In an internal combustion engine having a bed, a crank-shaft journaled therein, a valve-rod provided with a head in juxtaposition to one side of the shaft, a tappet-plate carried by the head, and a governor-controlled grooved sleeve reciprocatively mounted upon said shaft; the combination of a vertically disposed pin extending from the engine bed upon that side of the shaft opposite the valve-rod head, an arm pivotally mounted upon the pin, the arm being extended crosswise of the sleeve and having its free end disposed upon the opposite side of said sleeve from that of its point of oscillation, a rectangular tappet-seat at its free end, the tappet-seat being upon the same horizontal plane as the valve-rod tappet, and means depending from the arm intermediate of its length for engagement with the sleeve groove whereby the free end of said arm is caused to move in or out of the path of travel of the valve-rod tappet. 115

5. An internal combustion engine comprising a bed, a crank-shaft journaled therein, an arbor in gear connection with the crank-shaft, a spring-controlled reciprocative valve-rod, a forked head carried by the valve-rod engageable with the arbor, an ear extending from the head, a tappet-plate secured to the ear, a governor-controlled grooved sleeve reciprocatively mounted upon 130

the crank-shaft, a pivot-pin extending upwardly from the engine bed, an arm having one end journaled upon the pivot-pin, the arm being extended crosswise over the sleeve 5 and having its free end disposed upon the opposite side of said sleeve from that of its point of oscillation, a tappet carried at the free end of the arm for engagement with the valve-rod head tappet, and a stud extending 10 from the arm intermediate of its ends engageable with the sleeve groove whereby

said arm is oscillated when the sleeve is moved under control of the governor.

In testimony that I claim the foregoing I have hereunto set my hand at Milwaukee, 15 in the county of Milwaukee and State of Wisconsin in the presence of two witnesses.

HARRY W. BOLENS.
